Munn & Co.

Attorney

UNITED STATES PATENT OFFICE.

SIDNEY STERLING, OF LOS ANGELES, CALIFORNIA.

ANTIMARRING MEANS FOR PICTURE FRAMES.

Application filed June 12, 1926. Serial No. 115,688.

My invention relates generally to picture frames and the like and it is a purpose of my invention to provide extremely simple and inexpensive means associated with the picture frame for preventing marring of the walls should the frame be moved in cleaning or dusting.

A further purpose of my invention is the provision of means preferably associated with the screw eyes on the frame for attaching the picture hanging wire or cord to the frame or with any other means on the frame to which picture hanging means is connected, the means being associated with the screw eyes in such manner that the latter will be prevented from contacting with the wall to the extent of marring the latter when the frame is moved in the cleaning or dusting thereof.

20 I will describe only one form of antimarring means for picture frames and will point out the novel features thereof in claims.

In the accompanying drawing,

25 Figure 1 is a view showing in end elevation a picture frame hung from a wall with one form of anti-marring device embodying my invention applied to its screw eyes;

30 Figure 2 is an enlarged sectional view taken on the line 2—2 of Figure 1;

Figure 3 is a sectional view taken on the line 3—3 of Figure 2;

35 Figure 4 is a detail perspective view of the anti-marring device embodying my invention.

Referring specifically to the drawing, in which similar reference characters indicate similar parts in each of the several views, my invention, in its present embodiment, is shown associated with the conventional form 40 of screw eyes S threaded into the back of a picture frame F, to which screw eyes is usually connected a picture hanging wire or cord P for hanging the frame from a hook H or other form of support upon a wall W.

My invention in its present embodiment comprises a body of soft or yieldable material such as, for instance, felt, in the form 50 of a relatively thick disk 10 having an axial opening 11 extending therethrough and slit inwardly from its periphery in the plane of the disk, as clearly shown at 12, in Figures 3 and 4 to provide a pocket adapted to receive the eye of the screw S. The slit in the disk is preferably of such depth that

the eye of the screw must be forced into the material of the disk to bring its axial opening 11 into registration with the opening in the eye so that a relatively large portion of the periphery of the disk remains unbroken for engagement with the wall W.

With the disk 10 applied to the screw eye S in this manner, a grommet or hollow rivet 13 is passed through the openings in 60 the disk and eye and its ends then flared as at 14 to clampingly engage the opposite sides of the disk and thus firmly secure the latter in covering relation to the eye. In addition, the provision of the grommet 13 70 permits the picture hanging wire P to be threaded through the eye of the screw and then twisted upon itself in the usual manner to connect the wire to the eye.

In operation, and with the picture frame 75 F having my invention applied to its screw eyes, it will be clear that when the frame is hung upon the wall as shown in Figure 1, the unbroken portion of the periphery of the disks 10 will engage the wall instead 80 of the metal eyes of the screws S so that should the frame be moved such as when dusting or cleaning, the soft surface of the disks will readily slide over the surface of the wall without marring or otherwise damaging the latter.

It will be manifest that my invention can be quickly and easily applied to the conventional form of screw eye and but slightly increase the cost of the latter, which cost is 90 negligible as compared to the material advantage effected by its use in positively preventing damage to a wall, such as now occurs with the use of unprotected metal screw eyes.

95 It is to be understood that I do not wish to be limited to the precise material specified as other materials can be used for the purpose described.

Although I have herein shown and described only one form of anti-marring means for picture frames embodying my invention, it is to be understood that various changes and modifications may be made therein without departing from the spirit of 105 the invention and the spirit and scope of the appended claims.

I claim as my invention:

1. In combination, a screw eye, a body 110 formed of soft material and slit to receive the eye of the screw, said body having an opening adapted to register with the opening

in the eye when the body is applied to the latter and a grommet extending through the opening and through the eye of the screw for securing the body on the eye.

5. 2. As an article of manufacture, a screw eye, a disk shaped body formed of felt and slit inwardly from its periphery to receive the eye of the screw, said body having an opening therethrough adapted to register 10 with the opening in the eye when the body is applied to the latter, and a grommet extending through the openings in the body and eye for securing the body to the screw.

3. In combination, a screw eye, a disk-shaped body formed of felt and having its periphery slit circumferentially in the plane of the body to form a pocket for receiving the eye of the screw, said body having an axial opening extending therethrough adapted 20 to register with the opening in the eye when the body is applied to the latter, and a grommet extending through the openings in the body and the eye and clampingly engaging the opposite sides of the body for 25 securing the latter to the eye.

4. As an article of manufacture, an anti-marring device for picture frames comprising a tubular body, formed of soft material and slit to receive the eye of a screw in 30 such manner that when applied to the screw, the opening in the body will register with the opening in the eye.

5. As an article of manufacture, an anti-marring device for picture frames comprising

ing a tubular body formed of soft material 35 and slit to receive the eye of a screw in such manner that when applied to the screw the opening in the body will register with the opening in the eye, and a grommet adapted to be passed through the openings in the 40 eye and body for securing the body to the screw.

6. As an article of manufacture, an anti-marring device for picture frames comprising a disk-shaped tubular body formed of 45 soft material and having a peripheral slit in which the eye of a screw is adapted to be received with the opening in the eye registering with the opening in the body.

7. In combination, a screw eye, a body 50 formed of yieldable material in covering relation to the eye of the screw, and means for securing the body to the screw in a manner to permit a picture hanging wire to be threaded through the opening in the 55 eye, said means comprising a grommet extending through the eye and body.

8. In combination, an eye screw, a body 60 formed of yieldable material, in covering relation to the eye of the screw, said body having an opening therethrough, and means for holding the body on the eye of the screw, with the opening in the body registering with the opening in the eye of the screw so 65 as to permit a picture hanging wire to be threaded through the openings.

SIDNEY STERLING.
